UNITED STATES PATENT OFFICE

FRENCH H. MOREHEAD, OF BOSTON, MASSACHUSETTS

APPARATUS FOR MAKING SAND CORES

Application filed February 8, 1928. Serial No. 252,771.

My present invention relates to methods and apparatus for making sand cores for casting tubular articles such as pipe, hydrant barrels, columns and the like of the type referred to in my co-pending application Serial No. 252,770, filed February 8, 1928.

As is well known to those skilled in the art, cores for long articles cast in substantially horizontal position are bent or distorted during casting by the pressure of the molten metal which tends to float the core. Attempts have been made to counteract this effect as for instance by subjecting the core after it is in place in the mold to stresses which tend to bend the core in the direction opposite to that produced by its tendency to float. The tendency of the core to float and thus be distorted can also be overcome by employing a core which is bent the right amount during its manufacture so that when the metal is poured the tendency to float brings it to the desired straight position. My present invention, therefore, has for its object a method and apparatus for making suitable bent cores rapidly and economically.

It is the object of the invention to produce by rotation cores adapted to overcome the above mentioned difficulties and which may be straight but not of circular cross section or to produce bent cores which may or may not be of circular cross section, any of which may be uniform or variable in cross section from end to end.

In the practice of my present invention suitable core sand is shaped upon an arbor while the arbor is flexed by a suitable force applied thereto. Thereafter the arbor is permitted to straighten or return to its original condition and thereby flex the body of sand shaped thereon. By my preferred procedure the core sand is deposited on a rotating arbor and is trimmed by a suitable knife as the arbor is rotated, the arbor being flexed or bent by a suitable mechanism. The invention provides a simple and effective method and apparatus for producing suitable cores as fast as straight ones and the cores can be employed in ordinary molds without employing any means to bend them after they are placed in the mold, or to hold them

against bending due to their tendency to float in the molten metal; therefore, casting with cores made in accordance with the process embodying my invention is much simplified and cheapened. Tubular articles produced by the use of the cores so made have a uniform cross section and therefore metal is saved. The number of defective articles which must be rejected is reduced and the articles have a longer life with no additional expense in manufacture.

Before explaining in detail the present invention, and the method or mode of operation embodied therein, it is to be understood that the invention is not limited in its application to the details of construction and arrangement of parts illustrated in the accompanying drawings, since the invention is capable of other embodiments and of being practised or carried out in various ways. Also it is to be understood that the phraseology or terminology employed herein is for the purpose of description and not of limitation, and it is not intended to limit the invention beyond the terms of the several claims hereto appended or the requirements of the prior art.

The invention will be more clearly understood from the following description, in conjunction with the accompanying drawings, in which

Fig. 1 is an elevational view partly in section of an apparatus embodying the invention;

Fig. 2 is a side sectional view of the same.

Fig. 3 is a sectional view taken on the line 3-3 of Fig. 2, and

Fig. 4 is an elevational view of the core produced by the practice of the invention.

A suitable apparatus embodying my invention may comprise a suitable support 10 having a frame 11 extending upwardly near each end of the apparatus for rotatably supporting rolls 12 upon which a normally straight arbor 13 rests. A cross member 14 is pivoted at one end to the frame 11 and detachably mounted thereto, as by a bolt 16 and a nut 17, at its outer end. A roll 15 is rotatably mounted in the cross member 14 so as to engage the arbor and hold the same

100

against the rolls 12. The arbor 13 is provided with a groove 18 near each end thereof for engagement with the rolls 12 and 15.

An outer frame 20 extends upwardly from the support 10 and is spaced from each frame 11 and is provided at its top with a cross member 21 having a portion 22 forming part of a journal for an eccentric or cam 23 detachably mounted upon the arbor in any suitable manner, as by a set screw 241. A cross member 24 is pivotally mounted at one side of the top of each frame 20 and is detachably secured to the other side as by a nut 25 and bolt 26. A shaping knife 27 is secured, as by screws 28, to a cross member 29 connecting frames 11.

The arbor may be rotated by a mechanism at each end, including a shaft 30 provided at one end with a spline or key 31 adapted to engage a slot or keyway 32 in the ends of the arbor. The other end of the shaft 30 is connected by a universal joint 33 to a shaft 34 rotatably mounted in the frame. The driving mechanism at each end of the arbor may be connected to operate in synchronism. For this purpose each shaft 34 may be provided with a gear 35 operatively connected with a gear 36 near each end of a shaft 37 rotatably mounted in the frame. This mechanism may be operated from any suitable source of power transmitted for example to a pulley 38 mounted upon the shaft 34.

A suitable hopper 40 is supported in any convenient manner, as by a frame 41, above the arbor 13 and is provided at its lower end with a chute 42 extending to a point close to the arbor. A riddle 43 is suspended within the hopper and is provided with upwardly extending arms 44 pivotally mounted upon shafts 46 secured in a frame 47 extending upwardly from the hopper.

In the manufacture of cores, power is supplied to rotate the arbor 13 and during its rotation the eccentrics 23 will cause bending or flexure of the arbor 13. A suitable mixture of sand and binder is introduced into the riddle 43 and the latter is vibrated, whereupon the sand and binder mixture passes downwardly through the hopper 40 and chute 42 and is deposited upon the arbor 13 with considerable impact. The sand will cling to the surface of the arbor due to the presence of the binder admixed therewith, and will accumulate upon the arbor until engaged by the effective edge of the shaping knife 25. The knife will shear off any excess of sand and binder mixture and shape the same. The supply of sand mixture is then cut off and the arbor rotated through one or two revolutions thereafter. The amount of flexure of the arbor will be controlled by the character of the eccentrics employed. When the flexed arbor having the cylindrical body of sand mixture thereon is removed from the apparatus, it will tend to straighten and

thereby impart a curvature to the accumulated sand mixture 46 to provide a crooked core, as shown in Fig. 4.

I claim:

1. The method of making sand cores which comprises flexing an arbor, shaping a suitable sand mixture around said arbor, and thereafter permitting it to straighten and flex the core. 70

2. The method of making a sand core which comprises depositing a sand mixture upon a revolving arbor, flexing the arbor during its rotation, and shaping said mixture on the arbor by a knife as the arbor rotates. 75

3. In an apparatus for making sand cores, 80 a rotatable arbor, means for depositing a suitable sand mixture on the arbor, a knife for shaping said mixture, and a cam acting upon the arbor to flex it.

4. In an apparatus for making sand cores, 85 a rotatable arbor, means for depositing a suitable sand mixture upon the arbor, a knife for shaping said mixture, means for rotatably supporting said arbor at spaced points, and a cam acting upon said arbor at a point 90 spaced from said supporting means to flex the arbor.

In testimony whereof I affix my signature.
